RAILWAY TRAFFIC CONTROLLING APPARATUS

John M. Pelikan, Greentree, Pa., assignor to The Union Switch & Signal Company, Swissvale, Pa., a corporation of Pennsylvania

Application March 20, 1937, Serial No. 132,067

6 Claims. (Cl. 246—3)

My invention relates to railway traffic controlling apparatus of the type involving switches and signals controlled by manually operable means, such, for example, as levers located at a control point, and has for an object the provision of means for accomplishing the control and indication for switches and signals with a minimum number of line wires between the control point and the controlled device.

10 I will describe several forms of apparatus embodying my invention, and will then point out the novel features thereof in claims.

In the accompanying drawings, Fig. 1 is a diagrammatic view showing one form of apparatus embodying my invention for controlling and indicating a switch over a pair of conductors, comprising a switch control conductor and a common conductor, and for controlling and indicating one or more signals over a pair of conductors, comprising a signal control conductor and the same common conductor as is used for controlling a switch. Fig. 1A is a diagrammatic view showing a modification of the circuits for relays 1WPR and 1ZR in Fig. 1, and also 15 showing circuits for a switch indication relay 1WAR. Fig. 2 is a diagrammatic view showing a modification of the control and indication circuits in Fig. 1. Fig. 2A is a diagrammatic view showing a modification of the circuits for relays 1WPR and 1ZR in Fig. 2. Fig. 3 is a diagrammatic view showing the ordinary release relays 2HR and 1WR instead of the corresponding slow 20 release relays in Figs. 1 and 2, and showing circuits for slow release repeater relays 2HRPR and 25 1WRPR.

30 Similar reference characters refer to similar parts in each of the views.

Referring first to Fig. 1, the reference characters 3 and 3a designate the track rails of a 35 track section E—F which is separated by means of insulated joints 4 from adjacent portions of a stretch of railway track. Track section E—F is provided with a track circuit including a battery 5 connected across rails adjacent one end 40 of the section and a track relay TR connected across the rails adjacent the opposite end of the section.

Located in section E—F is a track switch 1. This switch is operated by a mechanism M which 45 is controlled by a slow release polarized switch control relay 1WR.

Adjacent the point E, signals 2RA and 2RB are 50 located for governing traffic movements over switch 1 from left to right as shown in the drawings, which I will assume is the eastbound direc-

tion. Signal 2LA, adjacent point F, is for governing westbound traffic movements over switch 1 in the normal position in which it is shown in the drawings. The signals are controlled in part by a slow release polarized signal control relay 5 2HR.

In each of the views, the contacts operated by the various relays or other devices are identified by numbers, such numbers having distinguishing prefixes from which they are separated by a dash when the contacts are shown apart from the relay or other device by which they are operated. The prefix for each of these contact numbers comprises the reference character for the respective relay or other device. 10 For example, contact 1WR—12, shown in the operating circuits for switch mechanism M, is identified by the number 12 separated by a dash from the prefix 1WR which is the reference character for relay 1WR by which this contact is 15 operated. Similarly, contact 2HR—41, shown in the operating circuits for signals 2RA and 2LA, is identified by the number 41 separated by a dash from the prefix 2HR which is the reference character for relay 2HR by which this contact is 20 operated. 25

Switch control relay 1WR and signal control relay 2HR are manually controllable by devices such, for example, as levers 1V and 2V, respectively, located at a control point which may be an 30 interlocking tower or dispatcher's office. Each of these levers has a normal position *n*, in which it is shown in the drawings, and a reverse position *r* to the right. Lever 2V has also a reverse position *f* to the left. 35

The normal and reverse energizing circuits for relay 1WR include a switch control conductor 9 and a common conductor C. The normal and reverse energizing circuit for relay 2HR include 40 a signal control conductor 30 and common conductor C.

The circuits for relays 1WPR and 2HR are supplied with current for energizing these relays from a suitable source, such, for example, as batteries 1Q and 2Q located at the control point. 45 The positive terminal of battery 2Q and the negative terminal of battery 1Q are connected together and with common conductor C. Battery 1Q has a positive terminal B, and battery 2Q has a negative terminal N. 50

A polarized switch indication relay 1WPR is controlled by polar contact 16 of switch control relay 1WR, and by two pairs of pole changing contacts designated by the reference characters M—a and M—b which are operated in conjunc- 55

tion with switch 1. Pair M—*a* comprises contacts 15 and 17 which are closed at their back points only when switch 1 occupies the normal position in which it is shown in the drawings, 5 and which are closed at their front points when switch 1 is moved away from the normal position. Pair M—*b* comprises contacts 18 and 19 which are closed at their front points when switch 1 is away from its reverse position, and which are closed at their back points only when switch 1 occupies its reverse position.

Relay 1WPR is energized by current of one polarity or the other only when switch 1 occupies a position corresponding to the position of 15 polar contacts 1WR—13 and 1WR—14 shown in the operating circuits for switch mechanism M. When switch 1 is between its normal and reverse positions, both pairs of contacts M—*a* and M—*b* are closed at their front points, and hence relay 1WPR will be shunted by either jumper 27 or 28, each of which connects a front point of pair M—*a* with a front point of pair M—*b*.

When relay 1WPR is energized, a switch indication repeater relay 1ZR is also energized by constant current, such, for example, as is supplied from terminal B of battery 1Q, over the front point of contact 20 of relay 1WPR. When relay 1WPR is deenergized, relay 1ZR is energized by current from terminal 1B of a source of periodically interrupted current.

As here shown, periodically interrupted current is provided by passing current from terminal B, through contact 32 of a coding device D. Coding device D may be of an oscillatory type operating at a low frequency of the order of 120 cycles per minute, and provided with a self-control contact 6, as well as with contact 32 for periodically interrupting the current supplied from terminal B, and also having a winding designated by the numeral 120 corresponding to the frequency of operation of coding device D. The contacts of coder D are biased by a coil spring 7 to the position shown in the drawings, when the coder is deenergized. Coder D is connected directly with terminal C and, through its contact 6, is connected with terminal B, and is therefore constantly in operation.

The switch control circuits for energizing relay 1WR include the winding of a second switch indication relay 1WKR in series with the winding of relay 1WR, and also include contact 1ZR—11 of relay 1ZR and contact 10 of a lock relay 1LR. Relay 1LR may be controlled by track relay TR and by an approach locking relay, or by any other means desired. The approach locking relay for controlling relay 1LR may be controlled in any suitable manner, such, for example, as shown for relay L in Letters Patent of the United States No. 1,956,851, granted May 1, 1934, to C. A. Brooks and J. M. Pelikan for Railway traffic controlling apparatus.

A signal indication relay 2HF is energized by periodically interrupted current supplied from terminal 1B to circuits controlled by signal control relay 2HR and by signal repeater relays 2RGPR and 2LGPR. Relay 2LGPR is controlled by signal 2LA, and is energized only when signal 2LA is indicating stop. Relay 2RGPR is similarly controlled by signals 2RA and 2RB.

As here shown, signals 2RA, 2RB and 2LA are of the searchlight type, but may be of any other suitable design. As shown in the drawings, each of these signals comprises a member 43 mounted to oscillate between two extreme positions, and controlled by a winding 42 and by a permanent

magnet or an electromagnet, not shown, so that when winding 42 is energized, member 43 will move to one of its extreme positions or the other according as winding 42 is energized by current of normal or reverse polarity. Member 43 is biased to a middle position in which it is shown in the drawings, and which it occupies when winding 42 is deenergized. Member 43 carries three roundels G, R and Y arranged to cooperate with an electric lamp *i* in such manner that when member 43 is in its middle position, roundel R is in front of lamp *i*, whereas when member 43 is swung to the left or to the right, roundel Y or roundel G, respectively, is placed in front of lamp *i*. As shown in the drawing lamp *i* is above the roundels, but the lamp is placed in this location for purposes of illustration, and it is to be understood that in actual practice the lamp is directly behind the roundels. Each lamp *i* is connected directly with terminals *x* and *o* of a suitable source of current and is, therefore, constantly lighted.

Each of the signals operates a contact 22 which is closed when the member 43 occupies the R or Y positions but is open when member 43 occupies the G position. Each of the signals 2RA and 2LA also operates a contact 23 which is closed when the member 43 occupies the R or G position but is open when member 43 occupies the Y position. A signal of this type is disclosed and claimed in Letters Patent of the United States No. 1,864,224 granted to Wesley B. Wells on June 21, 1932, for Light signals.

The signal control circuits for energizing relay 2HR include the winding of a second signal indication relay 2HKR in series with the winding of relay 2HR, and also include back contact 31 of the first signal indication relay 2HF.

The second switch indication relay 1WKR controls an indication device here shown as an electric lamp 1K. The second signal indication relay 2HKR also controls an indication device here shown as an electric lamp 2K.

Referring next to Fig. 1A, relay 1WPR is here controlled only by pole changing pairs M—*a* and M—*b*, and is, therefore, merely a switch repeater for switch 1. In Fig. 1A, a switch indication relay 1WAR is controlled by relays 1WR and 1WPR similarly to the manner in which relay 1WPR in Fig. 1 is controlled by relay 1WR and by switch 1. In Fig. 1A, relay 1ZR is controlled by relay 1WAR similarly to the manner in which relay 1ZR in Fig. 1 is controlled by relay 1WPR.

In Fig. 2, the circuits for energizing relays 1WR and 1WPR are exactly like those shown in Fig. 1. Switch indication repeater relay 1ZR shown in Fig. 2, is however, of the slow release type instead of the ordinary type shown in Fig. 1. A second slow release switch indication repeater relay 1ZPR, controlled by a front contact of relay 1ZR, is also shown in Fig. 2. The first circuit for relay 1ZR is controlled by a front contact of relay 1WPR, as in Fig. 1, but the second circuit for relay 1ZR is here energized by constant current, and includes a back contact of relay 1ZPR as well as a back contact of relay 1WPR.

Relay 2HF, in Fig. 2, is of the slow release type instead of the ordinary type shown in Fig. 1. Relay 2HR is here controlled by a front contact of 70 relay 2HF instead of by a back contact as in Fig. 1. In Fig. 2, relay 2HF is energized by current from terminal B, instead of by current from terminal B1 as in Fig. 1. Two circuits for relay 2HF are controlled by relays 2LGPR and 2RGPR.

in conjunction with a front contact and polar contacts of relay 2HR. A third circuit is added for relay 2HF controlled by a back contact of relay 2HR.

5 In Fig. 2A, as in Fig. 1A, relay 1WPR is merely a switch repeater for switch 1. The first slow release switch indication repeater relay 1ZR is here controlled by circuits including not only a front contact of relay 1WPR, as in Fig. 2, but also including polar contacts of relays 1WR and 1WPR, and in some instances also including a back contact of relay 1ZPR. The circuit for relay 1ZPR, and the circuit for relay 1ZR through a back contact of relay 1WPR, are exactly similar to the corresponding circuits shown in Fig. 2.

10 In Fig. 3, the slow release relays 1WR and 2HR of Figs. 1 and 2 are replaced by ordinary relays which control slow release switch and signal control repeater relays 1WRPR and 2HRPR, respectively. With this arrangement, the switch and signals can be controlled from a longer distance than is possible with the slow release line relays of Figs. 1 and 2. This is because the ordinary relays require a lower operating current than do 15 slow release relays, and, therefore, the line drop is lower with the ordinary relays than with the slow release relays.

20 Having described, in general, each of the several forms of apparatus embodying my invention, I will now trace in detail the operation of these forms of apparatus.

25 As shown in the drawings, all parts are in the normal condition, that is, the switch and a signal control levers 1V and 2V, respectively, are in their normal position *n*; switch 1 is in its normal position; signals 2RA, 2RB and 2LA are indicating stop; coding device D is operating; relays TR, 2RGPR, 2LGP, 1WR, 1WPR, 1ZR, 1LR and 1WKR are energized; relay 1WAR of Fig. 1A, relay 2HF of Fig. 2, relay 1ZPR of Figs. 2 and 2A, and relay 1WRPR of Fig. 3 are also energized; relay 2HF of Fig. 1, relays 2HR and 2HPR of the various figures, and relay 2HRPR of Fig. 3 are deenergized; switch indicating lamp 1K is lighted, 30 lamps *i* of signals 2RA, 2RB and 2LA are lighted, and signal indication lamp 2K is unlighted.

45 I will first trace the operation of the form of apparatus shown in Fig. 1.

50 With switch control lever 1V in its *n* position, switch control relay 1WR is energized by current of normal polarity passing from terminal B, through contact 8 of lever 1V, winding of relay 1WKR, switch control conductor 9, contact 10 of relay 1LR, contact 1ZR-11, and the winding of 55 relay 1WR, to common conductor C. With relay 1WR thus energized by current of normal polarity, the normal operating circuit for mechanism M is closed, passing from terminal B, through contacts 1WR-12 and 1WR-13, mechanism M, and contact 1WR-14 to conductor C. With relay 1WR energized by current of normal polarity, and with switch 1 in the normal position, relay 1WPR is energized by a circuit passing from terminal B, through the back point of contact 15 of 60 pole-changing pair M-a, contact 16 of relay 1WR, winding of relay 1WPR, and back point of contact 17 of pair M-a, to conductor C. With relay 1WPR energized, relay 1ZR is also energized by its circuit passing from terminal B, through 65 the front point of contact 20 of relay 1WPR. Since the circuit for relay 1WPR is energized, relay 1WKR which is in series with relay 1WR is also energized, and hence switch indication lamp 1K is lighted by its circuit passing from terminal 70 B, through contact 21 of relay 1WKR.

75 With signals 2RA and 2RB indicating stop, signal repeater relay 2RGPR is energized by its circuit passing from terminal B, through contacts 22 and 23 of signal 2RA, contact 22 of signal 2RB, and the winding of relay 2RGPR to conductor C. With signal 2LA indicating stop, signal repeater relay 2LGP is also energized by its circuit passing from terminal B, through contacts 22 and 23 of signal 2LA, and the winding of relay 2LGP to conductor C.

10 I will assume that the leverman desires to reverse switch 1. He will therefore move lever 1V to its *r* position. Relay 1WR will then be energized by current of reverse polarity passing from battery 2Q, through conductor C, winding of relay 1WR, contact 1ZR-11, contact 10 of relay 1LR, conductor 9, winding of relay 1WKR, and contact 8 of lever 1V in the right-hand position, to terminal N. With relay 1WR energized by current of reverse polarity, switch 1 will be operated to the reverse position by its circuit passing from terminal B, through contact 1WR-12, contact 1WR-13 in the reverse position, mechanism M, and contact 1WR-14 in the reverse position, to conductor C.

15 With relay 1WR energized by current of reverse polarity, contact 16 of relay 1WR will open the circuit previously traced for relay 1WPR, causing relay 1WPR to become deenergized. With relay 1WPR deenergized, relay 1ZR will be 20 energized by periodically interrupted current passing from terminal 1B, through the back point of contact 20 of relay 1WPR, and the winding of relay 1ZR to conductor C. With relay 1ZR periodically energized, contact 1ZR-11 operated 25 by this relay will be closed periodically, and hence the circuit for relays 1WKR and 1WR will be closed only periodically. Relay 1WKR will therefore be periodically deenergized, causing the circuit for lamp 1K to be periodically opened, and 30 hence lamp 1K will display a flashing indication.

35 When switch 1 starts to move, contact pair M-a will close at its front points, thereby completing a circuit for relay 1WPR through the shunt connection 28, and thereby preventing relay 1WPR from becoming energized in any manner while switch 1 is between its normal and reverse positions.

40 When switch 1 completes its movement and is locked in the reverse position, contact pair M-b will close at its back points, thereby opening the circuit through the shunt connection 28. With pair M-a now closed at its front points and pair M-b closed at its back points while contact 16 of relay 1WR is closed in the reverse position, a 45 second energizing circuit will be completed for relay 1WPR, passing from terminal B, through the back point of contact 18 of pair M-b, winding of relay 1WPR, contact 16 of relay 1WR in the reverse position, and back point of contact 19 of pair M-b, to conductor C.

45 Relay 1WPR, upon thus becoming energized, opens the circuit for relay 1ZR which is supplied with periodically interrupted current through the back point of contact 20 of relay 1WPR, and again closes the circuit supplying relay 1ZR with 50 constant current, from terminal B, through the front point of contact 20 of relay 1WPR. Relay 1ZR being again constantly energized, contact 1ZR-11 will be constantly closed, causing relay 1WKR to be constantly energized and switch indicating lamp 1K to be constantly lighted. When lamp 1K thus stops flashing, the leverman will 55 know that switch 1 has completed its movement and is locked in its reverse position in response 60 to the leverman's desire to reverse switch 1.

to the energization of relay IWR by current of reverse polarity.

I will assume that the leverman now desires to return switch I to the normal position. He will therefore return lever IV to its n position, causing relay IWR to again become energized in the normal direction by the circuit first traced for this relay. The second circuit traced for energizing relay IWR will not be opened at contact 10 of relay IWR , causing relay IWR to again become deenergized. With relay IWR again deenergized, relay IZR will again be periodically energized, causing relay IWR to be periodically energized, which, in turn, will cause switch indicator lamp IK to display a flashing indication.

I will next assume that, with switch I again in its normal position, the leverman desires to clear signal 2LA . He will therefore move lever 2V to its r position, causing relay 2HR to become energized by current of reverse polarity passing from battery 2Q , through conductor C , winding of relay 2HR , contact 31 of relay 2HF , conductor 30 , winding of relay 2HCR , and contact 29 of lever 2V in its right-hand position to terminal N . Completion of this circuit causes relay 2HCR to close its contact 31 , thereby completing a circuit passing from terminal B , through contact 31 , for lighting signal indication lamp 2K .

With relay 2HR energized by current of reverse polarity, a circuit is completed for periodically energizing relay 2HF by current passing from terminal B , through contact 2LGPR-34 , contacts 35 and 36 of relay 2HR , and the winding of relay 2HF to conductor C . Relay 2HF , being periodically energized, will periodically open its contact 31 in the circuit previously traced for relays 2HCR and 2HR , causing contact 31 of relay 2HCR to be periodically opened. Lamp 2K will, therefore, display a flashing indication.

With relay 2HR energized by current of reverse polarity, a circuit will be completed for causing signal 2LA to be operated to its Y or G position which may be selected in accordance with traffic conditions in advance. Only a portion of this circuit is shown, including contacts IWR-38 , IWR-39 , 2HR-40 , 2HR-41 in the right-hand position, and winding 42 of signal 2LA to conductor C . Upon the operation of signal 2LA to its G or Y position selected in accordance with traffic conditions in advance, contact 22 or contact 23 of signal 2LA will open, causing relay 2LGPR to become deenergized. With relay 2LGPR deenergized, contact 2LGPR-34 , operated by this relay, will open the circuit previously traced for relay 2HF , and hence contact 31 of relay 2HF will be constantly closed, causing relay 2HCR to be constantly energized, which, in turn, causes lamp 2K to be constantly lighted.

If the form of apparatus shown in Fig. 1 is modified as shown in Fig. 1A, switch indication relay IWAR is normally energized by a circuit passing from terminal B , through contact 44 of relay IWR , contact 45 of relay IWR in the left-hand position, contacts 46 and 47 of relay IWR , and the winding of relay IWAR , to conductor C . With relay IWAR thus energized, relay IZR is energized by constant current passing from terminal B , through the front point of contact 48 of relay IWR , and the winding of relay IZR , to conductor C . Switch indication lamp IK will therefore be constantly lighted.

If now the leverman causes relay IWR to be energized by current of reverse polarity in order to reverse switch I , the circuit traced for relay IWAR will be opened at contact 45 of relay IWR ,

causing relay IWAR to be deenergized. With relay IWAR deenergized, relay IZR will be periodically energized by current passing from terminal B , through the back point of contact 48 of relay IWAR , and the winding of relay IZR , to conductor C . With relay IZR thus periodically energized, contact IZR-11 in the circuit previously traced for relay IWR will periodically open, causing relay IWR to be periodically deenergized and, in turn, causing lamp IK to display a flashing indication until switch I is locked in the reverse position, which causes relay IWR to reverse its contact 46 to agree with contact 45 of relay IWR .

In the form of apparatus shown in Fig. 2, relay IWR is energized by circuits which are exactly similar to the circuits shown for this relay in Fig.

1. The circuits for relay IWR are also exactly like those for relay IWR in Fig. 1. The first circuit for relay IZR , including the front point 20 of contact 20 of relay IWR , is also exactly like the circuit for relay IZR through the front point of contact 20 of relay IWR in Fig. 1. The second slow release switch indication repeater relay IZPR is energized by a circuit passing from terminal B , through contact 49 of relay IZR . With contact 20 of relay IWR closed at the front point, relay IZR is constantly energized and, in turn, relay IZPR is also constantly energized.

If the leverman should reverse lever IV , causing relay IWR to be energized by current of reverse polarity, relay IWR will become deenergized, causing relay IZR to, in turn, also become deenergized. With relay IZR deenergized, relay IZPR will likewise be deenergized. When contact 50 of relay IZPR closes, a circuit will be completed for again energizing relay IZR , passing from terminal B , through contact 50 of relay IZPR , back point of contact 20 of relay IWR , and the winding of relay IZR , to conductor C . Energization of relay IZR causes relay IZPR to again become energized, which opens the circuit traced for relay IZR through contact 50 of relay IZPR . Relays IZR and IZPR will thus be alternately energized and deenergized as long as relay IWR is deenergized. Contact IZR-11 will therefore be periodically opened in the circuit for relay IWR , causing switch indication lamp IK to display a flashing indication.

As soon as switch I completes its operation in response to the reverse energization of relay IWR and is locked in its reverse position, relay IWR will again become energized by the second circuit traced for energizing relay IWR in the form of apparatus shown in Fig. 1. The switch indication lamp IK will then again display a steady indication.

As already pointed out, relay 2HF in Fig. 2 is of the slow release type, and is controlled by the back point of a contact of relay 2HR , as well as by the front point of this contact. Relay 2HF is controlled by a front contact of relay 2HF instead of by a back contact of this relay as in Fig. 1. Relay 2HF is here energized by constant current supplied directly from terminal B , instead of by periodically interrupted current supplied from terminal B in Fig. 1. With relay 2HR deenergized, as shown in the drawings, relay 2HF is normally energized by a circuit passing from terminal B , through the back point of contact 55 of relay 2HR , and the winding of relay 2HF to conductor C .

If, with the apparatus as shown in Fig. 2, the leverman moves lever 2V to the r position for clearing signal 2LA , relay 2HR will become ener-

gized by current of reverse polarity, as described for Fig. 1, thereupon opening its contact 55 at the back point and closing this contact at the front point. Upon the lapse of a brief period of time required because relay 2HF is slow releasing, contact 51 of relay 2HF will open the circuit for relay 2HR. Since relay 2HR is slow releasing, the front contacts of this relay will not open immediately. Before the front contacts of relay 2HR have had time to open, signal 2LA will have cleared and opened the circuit for signal repeater relay 2LGPR. Contact 53 of relay 2LGPR will thereupon complete a second circuit for energizing relay 2HF, passing from terminal B, through contact 53 of relay 2LGPR, contact 54 of relay 2HR in the right-hand position, front point of contact 55 of relay 2HR, and the winding of relay 2HF to conductor C.

It follows that, with the apparatus as shown in Fig. 2, signal indication lamp 2K will first become lighted on account of the energization of relay 2HCR when the circuit for relay 2HR is closed, and will then be extinguished during the interval of time between the opening of contact 51 of relay 2HF, when relay 2HR opens contact 55 at the back point, and the subsequent closing of contact 51 of relay 2HF, when contact 53 of relay 2LGPR completes the second circuit for relay 2HF.

In Fig. 2A, the circuits for relay 1WPR are exactly similar to the circuits shown for this relay in Fig. 1A. Relay 1ZR is normally energized by a circuit passing from terminal B, through contact 45 of relay 1WR in the left-hand position, contact 46 of relay 1WPR in the left-hand position, front point of contact 20 of relay 1WPR, and the winding of relay 1ZR, to conductor C. With relay 1ZR energized, relay 1ZPR is energized by a circuit passing from terminal B, through contact 49 of relay 1ZR, and the winding of relay 1ZPR, to conductor C.

If the leverman should desire to reverse switch 1, he will move lever 1V to its *r* position, causing relay 1WR to be energized by current of reverse polarity. The circuit just traced for relay 1ZR will therefore be opened at contact 45 of relay 1WR, and hence contact 49 of relay 1ZR will open the circuit for relay 1ZPR. With relay 1ZPR deenergized, a second circuit will be completed, after a brief period of time, for energizing relay 1ZR, passing from terminal B, through contact 45 of relay 1WR in its right-hand position, contact 1ZPR-56, and thence by the circuit previously traced for relay 1ZR through contacts 46 and 20 of relay 1WPR. Relay 1ZR, being again energized, causes relay 1ZPR to again become energized and open the circuit traced for relay 1ZR through contact 1ZPR-56. In this way, relays 1ZR and 1ZPR are alternately energized and deenergized, causing contact 1ZR-11, shown in Fig. 2, to be periodically opened in the circuit for relays 1WKR and 1WR.

When switch 1 moves away from its normal position in response to the reverse energization of relay 1WR, relay 1WPR will become deenergized, causing contact 20 of relay 1WPR to become closed at its back point. The action of relays 1ZR and 1ZPR will now be exactly the same as traced in connection with Fig. 2, until switch 1 is locked in its reverse position. A third circuit will then be completed for relay 1ZR, passing from terminal B, through contact 45 of relay 1WR in its right-hand position, contact 46 of relay 1WPR in its right-hand position, front

point of contact 20 of relay 1WPR, and the winding of relay 1ZR, to conductor C.

In Fig. 3, relays 1WR and 2HR are ordinary acting polarized relays instead of slow release relays as in Figs. 1 and 2. The slow release 5 polarized switch and signal control repeater relays 1WRPR and 2HRPR are controlled by relays 1WR and 2HR, respectively, and relays 1WRPR and 2HRPR similarly control circuits which are similar to those controlled by relays 1WR and 2HR, respectively, in the apparatus of Figs. 1 and 2.

With relay 1WR energized in the normal direction as shown in Fig. 3, relay 1WRPR is energized by a circuit passing from terminal B, through contact 57 of relay 1WR, contact 59 of relay 1WR closed in the left-hand position, winding of relay 1WRPR, and contact 58 of relay 1WR closed in the left-hand position, to conductor C. When the leverman causes relay 1WR 20 to be energized in the reverse direction, relay 1WRPR will be energized by current of reverse polarity passing from terminal B, through contact 57 of relay 1WR, contact 59 of relay 1WR in the right-hand position, winding of relay 25 1WRPR, and contact 58 of relay 1WR in the right-hand position, to conductor C.

When the leverman causes relay 2HR to be energized by current of reverse polarity for clearing signal 2LA, relay 2HRPR will become energized by current passing from terminal B, through contact 64 of relay 2HR, contact 66 of relay 2HR in the right-hand position, winding of relay 2HRPR, and contact 65 of relay 2HR in the right-hand position, to conductor C. 30 When the leverman causes relay 2HR to be energized by current of normal polarity, relay 2HRPR will be energized by current of normal polarity, passing from terminal B, through contact 64 of relay 2HR, contact 66 of relay 2HR in the 40 left-hand position, winding of relay 2HRPR, and contact 65 of relay 2HR in the left-hand position, to conductor C.

From the foregoing description and the accompanying drawings, it follows that in apparatus embodying my invention, operations of a track switch are governed by a switch control circuit including a switch control conductor and a common conductor, and that a switch indication device is controlled by indication circuits which also include the same switch control conductor and the same common conductor. A constant indication is displayed while the switch occupies the position which corresponds to the condition of energization of its control circuit. A 55 periodically interrupted indication is displayed while the switch is out of correspondence with the condition of energization of its control circuit.

Signal control circuits, including a signal control conductor and the same common conductor as is used in the switch control and indication circuits, govern the clearing of one or more signals. A signal indication device is controlled by indication circuits which include the signal control conductor and the common conductor. In one form of apparatus embodying my invention, the signal indication device is periodically operated from the time the signal control relay is energized until the signal corresponds to the 70 condition of energization of the signal control relay. In a second form of apparatus embodying my invention, there is a single interruption of the signal indication device when a signal is being cleared. The signal indication device is oper- 75

ated constantly as soon as the signal corresponds to the condition of energization of the signal control relay.

Although I have herein shown and described only a few forms of apparatus embodying my invention, it is understood that various changes and modifications may be made therein within the scope of the appended claims without departing from the spirit and scope of my invention.

Having thus described my invention, what I claim is:

1. In combination, an electrically controllable device operable to a first and a second position, a polarized control relay selectively responsive to current of normal and reverse polarities for closing its polar contacts in normal and reverse positions respectively, means controlled by said polarized control relay for operating said electrically controllable device to its first or its second position according as the polar contacts of said polarized control relay are closed in the normal or reverse position respectively, an indication relay, circuits controlled by said polarized control relay and by said electrically controllable device for energizing said indication relay only if said electrically controllable device is in a position corresponding to the closed position of the polar contacts of said polarized control relay, a repeater relay, a circuit controlled by a front contact of said indication relay for energizing said repeater relay by constant current, a second circuit controlled by a back contact of said indication relay for energizing said repeater relay by periodically interrupted current, manually controllable circuits controlled by a front contact of said repeater relay for energizing said polarized control relay by current of normal and reverse polarities, and indication means controlled over said manually controllable circuits by said repeater relay.

2. In combination, an electrically controllable device operable to a first and a second position, a polarized control relay selectively responsive to current of normal and reverse polarities for closing its polar contacts in normal and reverse positions respectively, means controlled by said polarized control relay for operating said electrically controllable device to its first or its second position according as the polar contacts of said polarized control relay are closed in the normal or the reverse position, an indication relay, circuits controlled by said polarized control relay and by said electrically controllable device for energizing said indication relay only if said electrically controllable device is in a position corresponding to the closed position of the polar contacts of said polarized control relay, a repeater relay, a circuit controlled by a front contact of said indication relay for energizing said repeater relay, a second repeater relay, a circuit controlled by a front contact of said first repeater relay for energizing said second repeater relay, a second circuit for energizing said first repeater relay controlled by a back contact of said indication relay in series with a back contact of said second repeater relay, manually controllable circuits controlled by a front contact of said first repeater relay for energizing said polarized control relay by current of normal and reverse polarities, and indication means controlled over said manually controllable circuits by said first repeater relay.

3. In combination, an electrically controllable device operable to a first and a second position, a polarized control relay selectively responsive to current of normal and reverse polarities for clos-

ing its polar contacts in normal and reverse positions respectively, means controlled by said polarized control relay for operating said electrically controllable device to its first or its second position according as the polar contacts of said polarized control relay are closed in the normal or the reverse position, a repeater relay, a circuit controlled by a front contact of said first repeater relay for energizing said second repeater relay, a second circuit controlled by a back contact of said second repeater relay for energizing said first repeater relay if said electrically controllable device is out of correspondence with said polarized control relay, manually controllable circuits controlled by a front contact of said first repeater relay for energizing said polarized control relay by current of normal and reverse polarities, and indication means controlled over said manually controllable circuits by said first repeater relay.

4. In combination, an electrically controllable device operable to a first and a second position, a polarized control relay selectively responsive to current of normal and reverse polarities for closing its polar contacts in normal and reverse positions respectively, means controlled by said polarized control relay for operating said electrically controllable device to its first or its second position according as the polar contacts of said polarized control relay are closed in the normal or the reverse position, a repeater relay, a second repeater relay, a circuit controlled by said polarized control relay and by said electrically controllable device for energizing said first repeater relay only if said electrically controllable device is in a position corresponding to the closed position of the polar contacts of said polarized control relay, a second circuit controlled by said polarized control relay and by said electrically controllable device and also by said second repeater relay for energizing said first repeater relay when said second repeater relay is deenergized while said electrically controllable device is out of correspondence with said polarized control relay, a third circuit controlled by a back contact of said second repeater relay for energizing said first repeater relay while said electrically controllable device is between its first and second positions, a circuit controlled by a front contact of said first repeater relay for energizing said second repeater relay, manually controllable circuits controlled by a front contact of said first repeater relay for energizing said polarized control relay by current of normal and reverse polarities, and indication means controlled over said manually controllable circuits by said first repeater relay.

5. In combination, an electrically controllable device operable to a given condition, a control relay, a manually controllable circuit for operating said control relay, means controlled by said control relay upon becoming operated for operating said electrically controllable device to said given condition, an indication relay, an indication circuit including a contact controlled by said electrically controllable device normally closed for energizing said indication relay but becoming opened when said electrically controllable device in response to operation of said control relay starts operating to said given condition, an indication

repeater relay, means controlled by a front contact of said indication relay for constantly energizing said indication repeater relay, means controlled by a back contact of said indication relay for periodically energizing said indication repeater relay, a contact of said indication repeater relay included in said manually controllable circuit for preventing energization of said control relay whenever this contact is open, and indication means controlled over said manually controllable circuit by said contact of the indication repeater relay.

6. In combination, a railway track switch, a polarized control relay, a manually controllable circuit for energizing said relay by current of normal or reverse polarity for operating its polar contacts to its normal or reverse position respectively, means controlled by polar contacts of said relay when operated to said normal or reverse

position for operating said switch to its normal or reverse position respectively, an indication relay, means controlled by said polarized control relay and by said switch for energizing said indication relay only when said switch and the polar contacts of said relay occupy corresponding positions, an indication repeater relay, means controlled by a front contact of said indication relay for constantly energizing said indication repeater relay, means controlled by a back contact of said indication relay for periodically energizing said indication repeater relay, a contact of said indication repeater relay included in said manually controllable circuit for preventing energization of said control relay whenever this contact is open, and indication means controlled over said manually controllable circuit by said contact of the indication repeater relay.

JOHN M. PELIKAN.
